Fig. 4

Fig. 6

FIG. 1 is a perspective view of the stuffed toy bird as viewed from the right front showing the embodiment of my new design;

FIG. 2 is a front view of the stuffed toy bird shown in FIG. 1;

FIG. 3 is a rear view of the stuffed toy bird shown in FIG. 1;

FIG. 4 is a right side view of the stuffed toy bird shown in FIG. 1;

FIG. 5 is a top view of the stuffed toy bird shown in FIG. 1; and

FIG. 6 is a bottom view of the stuffed toy bird shown in FIG. 1.

The left side view of the stuffed toy bird of my new design is substantially a mirror image of the view shown in FIG. 4.

I claim:

The ornamental design for a stuffed toy bird as shown and described.
